Patented July 1, 1969

214,557

CRANE BOOM SUPPORT

John L. Grove, Greencastle, Pa., assignor to Grove
Manufacturing Company, Shady Grove, Pa., a cor-
poration of Pennsylvania

Filed Feb. 27, 1968, Ser. No. 10,739

Term of patent 14 years

Int. Cl. D12—14

U.S. Cl. D14—3

FIG. 1

FIG. 2

FIG. 1 is an isometric view of the top, front and one side of a crane boom support, showing my new design; and

FIG. 2 is an isometric view of the top, rear and opposite side thereof, and the bottom being substantially plain.

I claim:

The ornamental design for a crane boom support, substantially as shown and described.
